[57] CLAIM

The ornamental design for a shoe tie stand, as shown and described.

DESCRIPTION

FIG. 1 is a front elevational view of a shoe tie stand showing my new design, the opposite side being a mirror image thereof;

FIG. 2 is a top plan view;

FIG. 3 is a right end elevational view, the opposite end being a mirror image thereof;

FIG. 4 is a front elevational view of an alternative embodiment utilizing a different material for the shoe supporting member.

FIG. 2

FIG. 4
